APPARATUS FOR APPLYING ELASTIC COVERS

Victor H. Hasselquist, Akron, Ohio, assignor to
 The B. F. Goodrich Company, New York, N. Y.,
 a corporation of New York

Application October 2, 1944, Serial No. 556,874

10 Claims. (Cl. 254—51)

This invention relates to apparatus for stretching elastic covers about surfaces, and is especially useful for applying ice-removing and other protective coverings to the surface of airfoils.

Elastic ice-removing covers have been secured about the leading edges of wings and other airfoils by rows of hollow tubular rivets secured to the skin of the airfoil and having threaded bores for receiving screws. The covers have been provided with rows of apertures along their margins for receiving fastening screws adapted to enter the threaded bores of the rivets, and fairing strips of sheet material, also having apertures for engaging the same screws sometimes have been applied over the margins of the covers.

Stretching of the covers to secure them in place under tension without damage to the covers or to the surfaces to be covered has been a difficult problem, especially where the parts are of large size. Where ice removing covers are to be applied these have often had air connections integral therewith which had to be inserted through apertures therefor in the skin of the airfoil, causing further difficulties of assembling. By the present invention an improved apparatus is provided for facilitating the assembling operation.

Objects of the present invention are to provide for preliminarily stretching the entire cover so as to position properly the air connections and then applying the cover about the leading edge of the airfoil in uniformly stretched condition, to provide for permitting application of one margin of the cover in advance of entry of the air connections, to provide for application of the covering at any position or attitude of the airfoil, and to apply the cover with the least amount of manual exertion.

These and other objects will appear from the following description and the accompanying drawings.

Of the drawings,

Fig. 1 is a plan view of the leading edge portion of an airfoil, a covering in the initial position of stretching and stretching apparatus attached thereto made in accordance with and embodying the invention, parts being broken away.

Fig. 2 is a cross section of the same, taken on line 2—2 of Fig. 1.

Fig. 3 is a similar cross sectional view showing the covering stretched to final position, and in dot-and-dash lines indicating an intermediate position of the covering and apparatus.

Fig. 4 is a view thereof taken on line 4—4 of Fig. 3.

Fig. 5 is a detail view of the slide showing the lock.

Referring to the drawings, the numeral 10 designates a leading edge portion of an airfoil to which an ice-removing covering 11 of elastic material is to be secured. The covering is formed with inflatable chambers 13, 14, 15 communicating with tubular connections 16, 17, 18. For securing the covering in place, tubular internally threaded rivets 19 are secured in apertures therefor in the skin of the airfoil and corresponding in location with one margin 11a of the covering, the rivets being arranged in spaced-apart relation spanwise along the airfoil, and correspondingly arranged apertures 20 for receiving securing screws 21 are formed in the margin of the covering.

The opposite margin of the covering is also provided with spaced apart apertures 30 for receiving fastening screws 31 and the airfoil is formed with correspondingly spaced apertures 32 with hollow internally threaded rivets 33 secured therein for receiving the screws 31. The rows of rivets 19 and 33 are spaced chordwise about the airfoil in such manner as to require the covering to be stretched when in place. Fairing strips of metal, such as 34, may be secured over the margins of the covering.

For receiving the connections 16, 17, 18, suitable through apertures 35, 36, 37 are formed in the skin of the airfoil.

For stretching the covering for securing it to the airfoil, straps 45 having an aperture 46 in one end and a U-shaped crotch 47 formed at the opposite end are secured at intervals along the airfoil by means of screws entering the hollow rivets 33. A pipe or other bar 48 is placed in the crotches of the straps adjacent the surface of the airfoil, and is secured in place by pins 49 inserted in apertures of the arms of the crotch. One or more strut members 50, depending upon the length of the covering spanwise of the airfoil, is fulcrumed on the bar 48, the strut members being each provided with a crotched end 51 for engaging over the bar 48 so as to be rotatably positioned thereabout. Each strut has a block 52 slideably mounted thereon. Cross apertures 53 are formed in each block for receiving a bar 54 parallel to bar 48. That portion of each block 52 in which the aperture 53 is located is arranged to project axially of the strut beyond the portion embracing the strut providing clearance for the bar 48 when the strut is rotatably positioned thereabout in the opposite direction, as in Fig. 3. A series of hooks 55 are adapted to engage over

bar 54. Each hook 55 has a pair of laterally open hooked fingers 56, 57 opening in opposed directions secured thereto and adapted to straddle the margin 11b of the covering at a screw aperture, thereto engage a screw 31 extending through the covering. The arrangement is such that a fairing strip may be superimposed upon the fingers 56 and screws placed through the fairing strip and the margin of the covering engaging the hooked fingers and projecting below the fingers 57 for engagement with the airfoil. The screws are not engaged by their threads but merely act as pins to secure the hooked fingers to the margin and due to the hooked arrangement, the fingers may be disengaged laterally from the screws 15 when once the screws are entered in the threads of the rivets 19. A frictional locking member 60 is mounted for swinging movement in the block 52 (see Fig. 5) and has an aperture 61 engaging loosely about the strut. A coil spring 62 seated 20 in the block and acting upon a plunger 63 urges the locking member to a position where it binds on the strut and resists movement thereof in the direction to the left of Fig. 5. The locking member acts as a ratchet pawl to prevent movement 25 of the block in one direction and permits substantially free movement in the opposite direction.

A weight 70 is secured to the extending end of the strut 50 for tensioning the covering.

In the operation of the invention, the covering being secured at its margin 11a to the airfoil and its margin 11b being temporarily secured, as by the hook members 55 to the bar 54 which is retained by the blocks 52, the blocks being held against sliding along the struts 50 by the frictional locking member, weights 70 are applied to the ends of struts 50 to stretch the covering to the desired dimension or to assist the operator in such stretching. The operator then forces the bar 54 downwardly, as seen in Fig. 2, about the bar 48 as a fulcrum to the full-line position of Fig. 3. During this movement the block 52 may be moved step by step toward the bar 48 to maintain the covering at the same stretched length. This is accomplished by tapping the depending end of the frictional locking member 60 on the right side as seen in Fig. 5 and thereby momentarily releasing the block to permit its sliding along the strut. When the strut reaches the position shown in full lines in Fig. 3, the screws 31 are aligned over the apertures in the rivets 33 and may be started into the threads of the rivets. This is made possible by the offset arrangement of that portion of the block 52 having the aperture 53 therein which permits close positioning of bar 54 to the surface of the airfoil and to the bar 48. The hooks 55 may then be removed from the screws 31 and the strut may be swung back to a horizontal position. Thereafter the screws are driven into place.

With the apparatus of the invention the ice-removing covering may be tensioned the desired amount throughout its length by applying 65 weights 70 thereto until it is stretched to the desired dimension. Thereafter the covering may be drawn about the leading edge of the airfoil without increasing or decreasing its tension and the air connections 16, 17, 18 will be in the desired positions to enter the apertures 35, 36, 37 at any desired location on the airfoil. As the margin 11b reaches its final position, the screws 31 70 may be entered partially in the threaded rivets, and the hooks 56, 57 may be laterally displaced 75

to release the stretching apparatus without disturbing the tension of the covering.

Variations may be made without departing from the scope of the invention as it is defined by the following claims.

I claim:

1. Apparatus for stretching an elastic covering about a curved surface while a margin of the covering is restrained against yielding with respect to said surface to position the opposite margin of said covering at a determinate location on said surface, said apparatus comprising means for holding said opposite margin of the cover, means for guiding said holding means and the held margin to said location, the guiding means comprising a strut embraced by said holding means with the latter mounted for movement along the strut and means at said location on said surface for bracing said strut.

2. Apparatus as defined in claim 1 in which said holding means comprises a clamp for releasably detaining said holding means at positions upon said strut.

3. Apparatus as defined in claim 1 in which said holding means comprises a structure embracing said strut and clutch means within said structure for releasably guiding said holding means at positions along the same.

4. Apparatus for stretching an elastic covering having a row of apertures along a margin thereof into a position in alignment with a row of securing apertures of an aircraft surface while an opposite margin of the covering is restrained against yielding with respect to said surface, said apparatus comprising means for holding the first said margin, means for guiding said holding means and the first said margin to said position, the guiding means comprising a strut embraced by said holding means with the latter mounted for movement along the strut, and means engageable at said position on said surface for bracing said strut.

5. Apparatus for stretching an elastic covering having a row of apertures along a margin thereof into a position in alignment with a row of securing apertures of an aircraft surface while an opposite margin of the covering is restrained against yielding with respect to said surface, said apparatus comprising means at said position for bracing a strut, a strut engageable with said bracing means and rotatably positionable thereabout, guiding means embracing said strut and moveable therealong, means on said guiding means for holding said first said margin of the covering, and means for moving said strut about said bracing means to stretch the covering.

6. Apparatus as defined in claim 5 in which said guiding means comprises a friction clutch for engaging said strut.

7. Apparatus as defined in claim 5 in which said guiding means comprises an apertured friction member arranged for embracing said strut, and means for resiliently holding it in such embracing relation against movement in one direction.

8. Apparatus for stretching an elastic covering having a row of apertures along a margin thereof into a position in alignment with a row of securing apertures of an aircraft surface while an opposite margin of the covering is restrained against yielding with respect to said surface, said apparatus comprising a bar extending along the surface of the aircraft at the position of desired attachment, a strut having an end adapted to engage said bar and rotatably positionable there-

about as a fulcrum, a guide embracing said strut and moveable therealong, means on said guide for holding the first said margin of the covering, means for moving said strut about said bar to tension the covering, and a moveable member on said guide adapted to frictionally engage said strut to lock said guide against movement along said strut in a direction toward said bar, said moveable member being displaceable to permit movement in such direction.

9. Apparatus for stretching an elastic covering having a row of apertures along a margin thereof into a position over a row of securing apertures of an aircraft surface while an opposite margin of the covering is restrained against yielding with respect to said surface, said apparatus comprising a bar extending along the surface of the aircraft at the position of desired attachment, a strut having end engage-

ment with said bar as a fulcrum, a guide moveable along said strut, means on said guide for holding the first said margin of the covering, said last named means being offset from said guide for positioning close to said bar by movement of said guide to align the apertures of said covering directly over said securing apertures, means for moving said strut about said bar to tension the covering, and means on said guide frictionally engaging said strut to retain said guide against movement along said strut toward said bar, said last-named means being displaceable to permit movement in such direction.

10. Apparatus as defined in claim 9 in which the means frictionally engaging said strut comprises a self-energizing clutch member engaging said strut and displaceable to permit movement of said guide therealong.
